FIG. 4.

UNITED STATES PATENT OFFICE

JAY CLEIS KROESEN, OF BELLEVILLE, NEW JERSEY

SOUND RECORD

Application filed April 7, 1928. Serial No. 268,080.

This invention relates to sound records and more particularly to light sensitive sound records which are formed on a flexible transparent film.

5 In the reproduction of sound waves by means of a record of the above type, a film is employed having variable light transmission properties by means of which a light ray of variable intensity is impressed upon a light 10 sensitive cell. The variations in the light ray produce corresponding variations in an electric current which is passed through the cell and may be utilized for the operation of any well known type of electro-magnetic sound 15 reproducing unit.

In accordance with the present invention, a plurality of relatively narrow sound record strips are located side by side on a flexible film as for example a standard motion picture 20 projection film. Apparatus associated with said film is arranged to pass light through a single record strip which may be selected at the will of the operator. In one form of the invention an endless film is provided with the record strip arranged in the 25 form of a helix thereabout. The source of light and light sensitive apparatus in this case are continually moved transversely of the film as the helix of the record strip progresses. The arrangement may be such that 30 the film is synchronized with the picture being projected, and may be adapted to play through a single reel or through an entire performance depending upon the relationship of the various parts.

The invention also consists in certain new and original features of construction and combinations of parts hereinafter set forth and claimed.

40 Although the novel features which are believed to be characteristic of this invention will be particularly pointed out in the claims appended hereto, the invention itself, as to its objects and advantages, the mode of its 45 operation and the manner of its organization may be better understood by referring to the following description taken in connection with the accompanying drawings forming a part thereof, in which

50 Fig. 1 is a front elevation of the film show-

ing the record strips incorporated thereon;

Fig. 2 is a side elevation of sound reproducing apparatus constructed in accordance with this invention;

Fig. 3 is a section taken along the line 3—3 55 of Fig. 2 showing the record film and the light aperture together with the driving mechanism;

Fig. 4 is an elevation of a modified form of apparatus in which the light aperture is 60 stationary and the film is progressively moved in a lateral direction; and

Fig. 5 shows a schematic arrangement of a modified form of apparatus in which the record strips are parallel to the line of movement of the film, and the light aperture progressively traverses the successive strips in alternate directions. 65

Like reference characters denote like parts in the several figures of the drawings. 70

In the following description and in the claims parts will be identified by specific names for convenience, but they are intended to be as generic in their application to similar parts as the art will permit. 75

Referring to the drawings more in detail, a motion picture film 10 of well known construction is shown in Fig. 1 having sound record channels or strips represented thereon at 1 to 9. These channels are formed obliquely of the film and extend progressively therearound in the form of a helix. The sound record strips comprise light and dark sections which are formed in any well known manner to represent sound vibrations and are capable of passing a variable beam of light. 80

Film 10, as shown more in detail in Figs. 2 and 3, may be passed around a pair of driving sprockets 11 and cooperating reels 12 which may be suitably placed for maintaining the film in its desired formation. The light projecting apparatus comprising a lamphouse 13 is supported on platform 14 which may be moved laterally as by screw 15, threaded bearing 16 being secured to base 14 in engagement with said screw. Aperture plates 17 are supported by base 14 on opposite sides of the film 10 and are provided with apertures 18 of proper formation to confine the trans- 95 100

mitted ray of light to a single sound record strip.

Light sensitive cell 20 supported in any convenient manner as by member 21^a from base 14 is suitably positioned to receive light projected from lamp house 13 which passes through aperture 18 of aperture plate 17. Light sensitive cell 20 is capable of receiving the varying ray of light passing through aperture 18 and translating said light into a pulsating electric current in a manner which is well known in the art. The electric current may then be utilized for the projection of sound waves in any convenient manner.

15 Screw 15 is suitably synchronized with sprockets 11 for causing a transverse movement of aperture 18 and associated apparatus so that said aperture follows the helical sound record strips as the film is advanced.

20 One method of synchronization has been indicated diagrammatically as gear 22 meshing with a pinion 21 carried by sprocket 11, and driving gear 23 associated with screw 15. The ratio of speed of sprocket 11 to that of screw 15 obviously depends upon the width 25 of the record strips and the total length of the endless film.

The arrangement above described may be operated simultaneously with the projection 30 of a motion picture. The sound record may comprise reproductions of the voices of the actors or may include orchestral selections which ordinarily accompany the picture. In the latter case the device is particularly useful in enabling small theatres to be equipped 35 with apparatus for reproducing large orchestras which frequently accompany showings of the picture in the larger theatres. The sound record film would be shipped with 40 the picture film and affords a simple means for insuring that the proper music accompanies the picture. Obviously it is equally useful in reproducing appropriate sounds to accompany the depicted action, such as music 45 or speech, and may be employed wherever sound sequences are to be reproduced.

Referring to the arrangement shown in Fig. 4, a mechanism is shown comprising an aperture plate 17 which is mounted upon a 50 suitable stationary framework 14 and provided with an aperture 18 for the purpose above described. Film 10 is carried upon sprockets 11B. One of said sprockets, may be driven by suitable gear train comprising 55 spur gear 30 and pinion 31. Pinion 31 may be secured to shaft 32 on which is loosely mounted sleeve 33 carrying collar 34 and sprocket 39. Sleeve 33 may be slidably secured on shaft 32 but caused to rotate in connection 60 therewith by any suitable means such as key 35. Sprocket 11B having sleeve 36 and collar 40 associated therewith may be slidably supported on rod 37 as by key 38.

Collars 34 and 40 are engaged by yokes 41 65 carried upon spanner 42 in which screw 43 is

threaded. Screw 43 is secured to and adapted to turn with spur gear 30. The relationship of the pitch of screw 43 to the gear ratio of gear 30 and pinion 31 is such that collars 34 and 40 together with their associated sleeves and sprockets are moved laterally by an amount adapted to maintain aperture 27 of aperture plate 25 in alignment with the helical sound record strip as the film is progressively advanced.

75 This arrangement operates in a manner similar to that described in connection with Figs. 2 and 3, although in this case the aperture plate and projecting apparatus remain stationary and the film is shifted laterally 80 as it advances. The essential feature, however, is to obtain progressive relative movement between the film and the aperture whereby the light ray may be always projected through a single record strip.

85 In the arrangement shown in Fig. 5, film 10A is provided with a plurality of vertical record strips and is adapted to be alternately moved in opposite directions whereby aperture 18 of aperture plate 17 may be caused to 90 pass over successive record strips in opposite directions. In this modification a pair of sprockets 11C are selectively driven from shaft 55 by means of clutch 56 and bevel gears 57 and 58. Clutch 56 may comprise a collar 95 59 having oppositely inclined gear teeth 60 and 61 on opposite sides thereof. Collar 59 is slidably mounted on driving shaft 55 but is keyed thereto as by sliding key 62.

Teeth 60 and 61 cooperate with similar 100 teeth carried by sleeves 63 and 64 which in turn are operatively associated with bevel gears 57 and 58 respectively. With the above arrangement of parts, sprockets 11C are selectively driven in opposite directions in accordance with the position of clutch 56 which 105 operates to alternately connect said gears to shaft 55. Clutch 56 is in turn operated by yoke 65 which cooperates with collar 59 and is carried by pivoted lever 66.

110 A cam 67 cooperates with the free end of lever 66 for alternately raising and lowering said lever for selectively bringing teeth 60 and 61 into engagement. Suitable means, such as spring 68, may be employed for holding lever 66 in engagement with cam 67. For intermittently rotating cam 67 a suitable distance to reverse the position of said lever, a pawl 68 and ratchet 69 are provided, said pawl being operated by bell crank lever 70 having armature 71 of electro-magnet 72 associated therewith.

115 When magnet 72 is energized, armature 71 is displaced laterally, moving pawl 68 downwardly and advancing ratchet 69 one position. Lever 66 then contacts with a portion of cam 67 having a different elevation, thereby throwing clutch 56 to an opposite position and reversing the direction of drive of film 10A.

Aperture 18 is moved laterally to the next successive sound record strip by screw 75 cooperating with base 76 carrying aperture plate 52. Screw 75 is rotated in accordance with the movement of ratchet 69 by a suitable gear train including bevel gears 77 and spur gears 78. The pitch of screw 75 is such that the movement imparted thereto in stepping the ratchet 69 around one position is sufficient to bring aperture 18 in alignment with the next successive sound record strip.

The apparatus shown in Fig. 5 is entirely controlled by electromagnet 72 and is so designed that an impulse of said electromagnet operates to reverse the direction of film 10A and simultaneously to shift aperture 18 to the next record strip. The film may thus be formed with a plurality of parallel records, each of which is adapted to play for any desired length of time, as for example, that corresponding to one reel of a motion picture. The various parallel strips can thus be made to correspond with the various reels of an entire feature. The apparatus would accordingly be operated simultaneously with the changing of projection machines when at the end of each reel.

The above described invention permits a motion picture film of standard size to be employed as a sound record whereby various standard parts may be used in connection therewith although the use of a film of this size is not essential. The aperture plate is shifted laterally with respect to the film, either continuously or intermittently, depending upon whether the sound record is of helical formation or extends parallel to the line of movement of the film. In either case a plurality of records are superimposed upon the same film and the total length of film required is correspondingly decreased.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. In a transparent light sensitive endless film, a narrow sound record thereon and disposed in helical relationship with respect thereto.
2. In a transparent light sensitive film, a sound record thereon of a width less than that of said film and progressively displaced laterally with respect thereto.
3. In an endless transparent light sensitive film, a sound record thereon of a width less than that of said film and progressively displaced laterally with respect thereto to form a continuous helical record.
4. In an endless transparent light sensitive

film, a sound record thereon transversely displaced with respect to said film and forming a continuous helical record.

5. An endless transparent light-sensitive film having a sound record thereon, said record being of a width less than that of said film, said record comprising a plurality of portions paralleling and adjacent each other but not paralleling the edges of the film, said portions forming a single continuous record.

In testimony whereof I have hereunto set my hand.

JAY CLEIS KROESEN.
